UNITED STATES PATENT OFFICE.

HENRY C. CREEDON, OF MEBANE, NORTH CAROLINA.

DAVENPORT.

No. 891,915.

Specification of Letters Patent.

Patented June 30, 1908.

Application filed March 10, 1908. Serial No. 420,237.

To all whom it may concern:

Be it known that I, HENRY C. CREEDON, citizen of the United States, residing at Mebane, in the county of Alamance and State 5 of North Carolina, have invented certain new and useful Improvements in Davenports, of which the following is a specification.

The present invention relates to an improved article of furniture of that type which 10 are commonly termed davenports and which are designed to be employed either as a couch or as a bed.

The object of the invention is to design a device of this character which can be readily 15 knocked down for shipping or storing purposes and in which the movable section is peculiarly connected to the fixed section in such a manner as to relieve the connecting members of all undue strain when swinging 20 the movable section from one position to the opposite position.

The invention further contemplates the provision of a novel mattress member which is formed in three loosely connected sections 25 and operates automatically to shield the upholstered portion thereof when the device is used as a bed.

For a full description of the invention and the merits thereof and also to acquire a 30 knowledge of the details of construction and the means for effecting the result, reference is to be had to the following description and accompanying drawings, in which:

Figure 1 is a perspective view showing the 35 device in the position assumed when used as a davenport. Fig. 2 is a perspective view of one end of the device when extended for use as a bed. Fig. 3 is a vertical sectional view with the movable section swung upwardly. 40 Fig. 4 is an end view with the movable section swung downwardly, the end frame being removed. Fig. 5 is a perspective view of the device when knocked down for shipment. Fig. 6 is an end view showing the movable 45 section folded downwardly against the various sections, the supporting frame being removed. Fig. 7 is a similar view showing the movable section as swung upwardly at the forward edge of the fixed section.

Corresponding and like parts are referred to in the following description and indicated in all the views of the drawings by the same reference characters.

Referring to the drawing the numeral 1 55 designates the fixed section of the davenport,

and 2 the movable section which is loosely connected thereto and is adapted to coöperate therewith to form either a couch or a bed as may be desired. The fixed section 1 is supported between the end frames 3 which may 60 be of any approved construction as shown on the drawing, and is preferably detachably connected to these frames to admit of the device being knocked down for shipment or storage. In the present instance the ends of the 65 fixed section 1 carry the hook members 4 which have a detachable and interlocking connection with corresponding sockets in the end frames 3, and form a rigid connection between the members when the device is assembled for use. Each of the sections 1 and 2 of the davenport is provided with bed springs of any suitable type and the said sections are connected by a mattress member comprising three loosely connected parts 5^a, 70 5^b and 5^c, the part 5^a of the mattress is permanently connected to the swinging section 2 and has the outer face thereof upholstered and the part 5^c is in a similar manner permanently connected to the fixed section 1 75 and has the outer face thereof covered with ticking or similar material. The intermediate part 5^b of the mattress has one face thereof upholstered in a manner corresponding to the part 5^a while the opposite face is 80 85 covered with ticking similar to the part 5^c.

In the specific construction of the fixed section it will be observed that the same comprises the longitudinal side pieces 1^a connected by the cross bars 1^b, the said cross 90 bars being slightly spaced from the ends of the side pieces. The corresponding ends of the sections 1 and 2 of the davenport are connected by means of the bars or links 6, the said links assuming a diagonal position as 95 shown in Fig. 6 when the swinging section is folded against the fixed section and the extremities of the links being pivotally connected to opposite sides of the sections. The outer end of each of the links 6 which is pivoted to the movable section 2 is formed with a laterally extending arm 6^a having a brace member 7 for the leg 8 loosely connected thereto. This leg 8 is pivotally connected to the opposite side of the swinging section 2 100 and is provided with a pin 9 loosely received within a slot 10 in the brace 7, the said slot communicating at its outer end with a lateral branch 10^a.

When the device is used as a davenport, 110

the movable section 2 is swung upwardly so as to form a back, the lateral arms 6^a of the links 6 coöperating with the braces 7 to move the pins 9 toward the inner ends of the slots 10 in which position the legs 8 are held in alinement with the braces. It will also be observed that when the movable section is swung into this position, the middle part 5^b of the mattress is folded against the part 5^c, 10 and the upholstered face of the middle part is uppermost and is exposed to view in connection with the upholstered part 5^a of the mattress. When it is desired to utilize the device as a bed the section 2 is first swung 15 downwardly upon the fixed section 1 as indicated in Fig. 7, and attention is directed to the fact that in this position of the parts the swinging section rests upon the fixed section and the links 6 are relieved of all strain. The 20 movable section is next swung upwardly upon the opposite side of the fixed section so that the ends thereof are in alinement with the lateral arms 6^a of the links. The pins 9 of the braces 7 are then automatically moved 25 to the outer ends of the slots 10 adjacent the mouths of the lateral branches 10^a of the slots. Upon a continued swinging movement of the section 2 the legs 8 automatically drop into operative position owing to the 30 action of gravity and the pins 9 move into the branches 10^a of the slots, thereby locking the legs in position and preventing any lateral swinging movement of the same. It will also be observed that when the movable 35 section is thus swung approximately into alinement with the fixed section the links 6 which are disposed between the cross bars 1^b of the fixed section and the end frames 3 rest upon the side pieces 1^a of the fixed section 40 and are thereby effectively reinforced and prevented from receiving any excessive strain. Attention is also directed to the fact that when used as a bed the middle part 5^b of the mattress is folded against the part 5^a of the 45 movable section 2 so as to protect the upholstered portion thereof and expose those portions covered with ticking. It will thus be apparent that I have provided an improved construction of davenport which is so 50 designed as to be readily knocked down for shipping or storing, and which can be readily transformed into a couch or a bed, the upholstered faces of the mattress member being wholly protected when used for the latter 55 purpose.

Having thus described the invention, what is claimed as new is:

1. A device of the character described comprising a fixed section, supports for the 60 fixed section, a movable section, links connecting the fixed section and movable section and provided with lateral arms, legs loosely connected to the movable section, and

braces coöperating with the lateral arms of the links to control the legs. 65

2. A device of the character described comprising a fixed section, supports for the fixed section, a movable section, links connecting the fixed section and the movable section and provided with lateral arms, legs loosely connected to the movable section, and brace members loosely connected to the lateral arms of the links and having a pin and slot connection with the legs for automatically 70 controlling the latter. 75

3. A device of the character described comprising a fixed section, a support for the fixed section, a movable section, links connecting the fixed section and the movable section, legs loosely connected to the movable section and provided with pins, and braces having an operative connection with the links and provided with slots loosely receiving the pins of the legs, the said slots communicating with lateral branches 80 designed to receive the pins to lock the legs against movement. 85

4. A device of the character described comprising a fixed section, a support therefor, a movable section, links loosely connecting the fixed section and the movable section and provided with lateral arms, legs loosely connected to the movable section and provided with pins, and brace members pivotally connected to the lateral arms of the links and 90 formed with slots loosely receiving the pins, the said slots communicating with the lateral branches 95 designed to engage the pins to lock the legs against movement.

5. In a device of the character described, 100 the combination of a fixed section formed with side pieces connected by cross bars, a support for the fixed section, a movable section, and links connecting the fixed section and movable section, the said links being 105 adapted to rest upon the side pieces of the fixed section when the movable section is swung into approximately the same plane therewith.

6. In a device of the character described, 110 the combination of a fixed section, a support for the fixed section, a movable section, links connecting the fixed section and movable section, legs loosely connected to the movable section, means coöperating with the 115 links for automatically controlling the legs, and a mattress formed in three loosely connected parts arranged to automatically expose different faces at different positions of the movable section. 120

In testimony whereof I affix my signature in presence of two witnesses.

HENRY C. CREEDON. [L. s.]
